WATCH BRACELET OR SIMILAR ARTICLE

Ananta Uengsakul, Bangkok, Thailand, assignor to Stelux
Manufacturing Company, Ltd., Kowloon, Hong Kong,
a corporation of Hong Kong

Filed July 3, 1968, Ser. No. 12,604

Term of patent 14 years

Int. Cl. D11—01

U.S. Cl. D45—4

The dominant features of my new design reside in the portions shown in full lines.

I claim:

The ornamental design for a watch bracelet or similar article, substantially as shown and described.
